MAGAZINE FOR FASTENER APPLYING
IMPLEMENT

Charles M. Lindstrom, East Greenwich, R. I., assignor, by mesne assignments, to Bostitch, Inc., a corporation of Rhode Island

Application March 29, 1945, Serial No. 585,486

14 Claims. (Cl. 1—49)

1

The present invention relates to improvements in fastener-applying implements and more particularly to implements of the plier-type adapted to be held and operated by one hand.

One object of the present invention is to provide an implement of the type indicated having more convenient means for loading it with fasteners such as U-shaped staples.

Another object is to provide in an implement of the type indicated improved means for withdrawing the fastener-feeding means or staple-pusher to permit loading the magazine with staples.

Another object is to provide in an implement of the type indicated means normally positioned to hold the staples in place in the staple-magazine and adapted to be withdrawn longitudinally thereof to permit the staples to be entered into the magazine.

Another object is to provide an implement of the type indicated having a slidable cover on the staple-magazine for normally retaining the staples in place therein and adapted to be withdrawn to open the magazine for receiving the staples and operative automatically to retract the staple-pusher.

Another object is to provide improved fastener-feeding and driving means for preventing the driving of a second fastener before the first one has been discharged from the implement.

Further objects of the improvement are set forth in the following specification which describes a preferred embodiment of the invention with one modified form thereof as illustrated by the accompanying drawings. In the drawings:

Fig. 1 is a side view of the complete implement shown as of the plier-type;

Fig. 2 is a longitudinal sectional view of the same showing the operating parts thereof;

Fig. 3 is a side view of the implement shown with the parts in position at the completion of driving and clinching a staple;

Fig. 4 is a plan view of the implement with the staple-applying arm shown in transverse section to illustrate the parts enclosed therein;

Fig. 5 is a longitudinal sectional view of the implement shown with the magazine-cover withdrawn and the pusher retracted and representing a stick or refill of staples as being inserted into the magazine;

Fig. 6 is a plan view of the complete implement illustrating the opening in the staple-applying arm for permitting staples to be inserted therethrough into the magazine;

Fig. 7 is a detailed plan view of the implement

2

with the staple-applying arm shown in transverse section;

Fig. 8 is an enlarged longitudinal sectional view of the forepart of the implement;

Fig. 9 is an enlarged front view of the same with certain of the parts shown in transverse section;

Fig. 10 is an enlarged view of the forepart of the implement showing the staple-driving means in position after a staple has been fed from the magazine;

Fig. 11 is a transverse sectional front view of the same;

Fig. 12 is a view similar to Fig. 10 showing the staple-applying means at the completion of driving and clinching a staple in the work;

Fig. 13 is a transverse sectional front view of the same; and

Fig. 14 is a side elevational view of the implement shown with a modified form of clinching means for stapling or tacking trouser-cuffs to the trouser-legs.

The present implement is generally similar to that illustrated and described in my United States Letters Patent No. 2,354,760, dated August 1, 1944, and the invention consists particularly in improvements therein. In general, the implement comprises a magazine 2 in the form of a trough-shaped arm, a fastener-applying arm 3 pivoted to the magazine-arm in overlying relation thereto, a clinching arm 4 at the opposite side of the magazine-arm from the fastener-applying arm, and a manually-operable force-multiplying lever 5 connected to actuate the clincher-arm.

The magazine 2 is of channel shape in cross-section comprising a bottom wall 8 and parallel side walls 9 extending upwardly therefrom. The forward ends of the side walls 9 of the magazine project beyond its bottom wall 8 and are folded

inwardly in flange-like portions 10, see Fig. 4. At the forward end of the magazine 2 the side walls 9 are extended upwardly in wing-like portions 12 formed with outwardly-projecting ears 13 bent at right-angles to provide abutments employed

for a purpose explained later. Mounted within the magazine-arm 2 and extending longitudinally thereof is a staple-support or core 15 across which U-shaped staples are adapted to be straddled and to feed therewith for delivery to the applying means. The staple-core 15 is of U-

shape or channel form in cross-section having a horizontal bottom wall 16 and vertical side walls 17, see Fig. 9, with flanges 18, see Fig. 4, at the top of the side walls folded inwardly toward each other. In the present form of construction of

the implement the side flanges 18 are relatively narrow throughout the greater portion of the length of the core 15, but adjacent the forward end they are extended to meet substantially at the center, see Figs. 8 and 9, in rectangularly-shaped portions or tabs 20. These meeting portions or tabs 20 are inclined upwardly toward the center of the core to provide a beveled rest for staples 3 having crowned heads or crossbars. In other cases the rest formed by the tab portions 20 may take different shapes either flat for ordinary U-shaped staples or with a curved contour for other forms of crowned staples.

The forward end of the core 15 is spaced a slight distance rearwardly of the inwardly-folded flanges 18 at the front of the magazine-arm 2 to provide vertical guideways or grooves 21 adapted to receive a slideable staple-driver 25 to be described later. Overlying the top of the core 15 at its forward end in spaced relation to the tabs 20 is a substantially U-shaped guard-member 22 having its sides welded or otherwise suitably secured to the upstanding wing-like portions 12 on the sides 9 of the magazine-arm 2. The forward edges of the sides of the member 22 are spaced rearwardly from the flanges 18 on the arm 2 to form a continuation of the grooves 21 for slideably mounting the staple-driver 25. The bottom transverse portion 23 of the guard member 22 is crowned or shaped to correspond with that of the tabs 20 to conform to the crowned crossbars of the staples as they rest on the tabs.

Referring particularly to the enlarged views, Figs. 8 to 13, inclusive, it is to be noted that the staple-rest comprising the tabs 20 is offset rearwardly from the forward edges of the side walls 17 of the core 15 to form relatively narrow shoulders 24 disposed below the rest and at the rear of the grooves 21. These shoulders 24 serve as detents or auxiliary rests for supporting each staple as it is fed off from the forward end of the core 15, see Fig. 12, it being noted by reference to Fig. 8 that the transverse portion 23 of the guard 22 is cut back to provide an open space above the shoulders 24. Above the shoulders 24 the sides 9 of the arm 2 are sheared to form extruded portions or lugs 31 which project inwardly therefrom for a purpose explained hereinafter.

The staple-driver 25 is in the form of a hardened metal blade of varying thickness from top to bottom and provided with relatively narrow guiding fins or runners 26 adapted to slide in the grooves 21 at the forward end of the magazine-arm 2. The blade of the driver 25 tapers in thickness from the top toward the bottom throughout its central portion and then is recessed rearwardly at its lower end. The lower recessed end of the driver 25 is thus formed with an offset shoulder 28 raised slightly above its forward edge. Near this end of the driver 25 is a circular hole 27 for connecting it with the staple-applying arm 3. On its rearward face the upper portion of the driver 25 is thickened to provide a substantially rectangular pad or projection 29 having its lower edge in the form of a horizontal shoulder 30 which overhangs the detent-shoulders 24 at the forward end of the core 15. The lower edge of the pad 29, that is the shoulder 30 formed thereby, is straight across the width of the driver, the purpose of this form of construction being explained hereinafter.

As before indicated, the staple-driver 25 is connected to be reciprocated by the arm 3, this connection comprising a stud 33 fastened in the forward end of the arm 3 and having its projecting portion engaging through the hole 27 near the

lower end of the driver. The staple-applying arm 3 is of inverted channel shape in cross-section with its side walls 34 tapering slightly toward its rearward end which is formed with semicircular ears 35 pivotally connected to the sides of the magazine-arm 2 by means of a crosspin 36, see Figs. 1 and 7. Substantially midway of its length the arm 3 is widened transversely by offset portions 37 of its side walls 34 while the forepart of the arm narrows again in conformity with its rearward portion. Along its rearward portion the side walls 34 of the arm 3 are joined together by a top wall 38, but forwardly thereof throughout its widened and front portions the top wall is cut away with an extended opening 40 to provide a window or doorway for inserting staples therethrough into the magazine-arm 2. Adjacent the forward end of the arm 3 its side walls are staked or punched to force the metal inwardly in a pair of substantially arcuate portions which form abutments 41, see Fig. 7, adapted to be engaged by the lower edges of the ears or lugs 35 which project from the sides of the arm 2, whereof to limit the upward movement of said arm 3 with respect to the arm 2 as indicated in Fig. 5. Suitably secured to the inner faces of the widened portions of the sides 34 of the arm 3, as by welding or riveting, are a pair of studs 45 having reduced central portions bounded by flanges as shown most clearly in Fig. 4. The studs 45 are engaged by the ends of the manually-operative lever 5 in a manner as later explained.

The clinching arm 4 is generally of channel shape in cross-section having its forward longitudinally-tapered portion offset below its main rearward portion, the sides of the latter being of greater depth. At its rearward end the sides of the arm 4 overlap the sides of the magazine-arm 2 and are provided with holes for receiving the cross-pin 36, previously mentioned, to pivotally connect the arm 4 to the arms 2 and 3. Positioned within the forward end of the arm 4 and welded or otherwise suitably secured to the walls thereof is a handened block 47 formed with clincher-grooves 48 of usual construction, see Figs. 11 and 13, which are in substantial alinement with the lower edge of the staple-driver 25.

The manually-operative lever 5 is of channel shape in cross-section with its rearward portion formed with a rounded bottom wall providing a hand-grip and its forward side walls 49 extended upwardly at an angle to adapt them to straddle the sides of the clincher-arm 4. A crosspin 50 projects through holes in the sides of the arm 4 and the side walls of the lever 5 for pivotally mounting the latter on the arm. The upper ends of the side walls 49 terminate in hooks 51 adapted to engage around the studs 45 which project inwardly from the walls of the staple-applying arm 3, see Figs. 4 and 5, whereby to connect the lever 5 for rocking said arm downwardly to reciprocate the driver 25 across the end of the magazine-arm 2. Rearwardly of the hook portions 51 of the lever 5 the sides 49 are formed with cam-faces 52 which operate on the studs 45 with an increased pressure or mechanical advantage, see Fig. 3, during the completion of driving and clinching the staples. That is to say, during the last end of the movement of the staple-driver toward the arm 4 the force of the lever 5 is multiplied to increase the clinching action as the legs of the staple are bent around and clinched on the under side of the work in the manner shown in Fig. 13. The clinching arm 4 is normally maintained in spaced relation

to the magazine-arm 2 and the staple-applying arm 3 through the means of a leaf-spring 55 of slightly bowed shape, shown best in Fig. 2. The rearward end of the spring 55 bears on the under side of the magazine-arm 2 and its forward end engages under the crosspin 56 while its central bowed portion bears against the bottom wall of the arm 4. A tongue 56 formed by the portion of the metal slit from the end of the spring 55 is bent upwardly and curved around the top of the pin 50 to connect this end of the spring therewith.

Referring particularly to Fig. 2 of the drawings, the staples s are held from rising up on the core 15 by means of a cover member 60 which overlies their crossbars and is slideable longitudinally of the magazine 2 to adapt it to open it for receiving the staples inserted through the window or door 40 in the top of the staple-applying arm 3. The cover 60 may be crowned along its central portion to adapt it to conform to the shape of conventionally-crowned staples and at its rearward end it is bent downwardly to form a tail-piece 61 adapted to be gripped in the fingers to draw the cover rearwardly along the top of the magazine 2. The cover 60 is formed with a relatively narrow slot 62 extending substantially its whole length as shown in Fig. 6 and intended for a purpose explained hereinafter. The cover 60 is maintained in position overlying the upper edges of the sides 9 of the magazine-arm 2 by means of a leaf-spring 63 bearing against the top wall of the staple-applying arm 3. As shown in Fig. 2 the rearward end of the spring 63 bears against the under side of the top wall 38 of the arm 3, its middle bowed portion bears against the top of the cover 60, and its forward end is fastened to the top wall 38 by a lug 64 of the metal slit from the top wall 38 and bent downwardly to project through a hole 65 in the spring. The spring 63 is slit longitudinally at its center throughout the greater portion of its length, the purpose of this construction being explained later hereinafter.

The staples s are advanced along the core 15 in the magazine-arm 2 by means of a staple-pushers 66 of usual construction adapted to overlie and straddle the core. Referring to Figs. 2, 4 and 5, the staple-pushers 66 is constructed of sheet-metal with a top wall 67 and downwardly-bent flanges or side walls 68. The side walls 68 extend forwardly beyond the forward end of the top wall 67 which is bent downwardly with a portion 69 therebetween as shown most clearly in Figs. 2 and 5. The forward edges of the side walls 68 are adapted to engage the legs of the rearmost staple in the magazine 2 to slide the whole series forward on the core 15. The staple-pushers 66 is slid forwardly along the core 15 under the tension of a helical spring 70, the forward end of which bears against the bent down portion 69 of the top wall 67. The rearward end of the spring 70 encloses a hollow stud 71 and bears against its flanged end 72 to press it against the crosspin 36 which pivotally connects the arms 2, 3 and 4. Referring to Fig. 4 of the drawings, it will be noted that the central portion of the pin 36 is reduced in diameter to form shoulders 73 which engage with the flange 72 on the stud 71 whereby the stud retains the pin against axial movement. The staple-pushers 66 is adapted to be withdrawn against the tension of the spring 70 by the retraction of the cover 60 along the top of the magazine-arm 2. For this purpose the staple-pushers 66 is provided with an upstand-

ing lug or finger 75 formed from a portion of the metal sheared from its top wall 67 and bent upwardly as shown most clearly in Figs. 5 and 7. The finger 75 is adapted to be engaged by the end of the slot 62 in the cover member 60 whereby the pusher may be drawn into the position shown in Fig. 5 with its rearward end engaging the crosspin 36 to limit its movement in this direction.

Referring to Fig. 4, it will be noted that the tail-piece or finger-grip 51 at the rearward end of the cover 60 is narrowed to form a pair of shoulders 76 at either side of its main portion which are beveled on their under sides, see Fig. 5. These beveled shoulders 76 are adapted to engage with the inclined ends of detent notches 77 at the ends of the side walls 9 of the magazine-arm 2 and thus tend to hold the cover in its forward position with its end abutting the U-shaped guard member 22. The more important function of the shoulders 76 and notches 77 is to raise the rearward end of the cover 60 as it is withdrawn. As the cover 60 is drawn rearwardly along the top of the arm 2 the beveled shoulders 76 will ride up out of the detent notches 77 to raise the rearward end of the cover and thereby increase the force of the spring 63 which holds it down. Consequently, the forward end of the cover will be pressed down as shown in Fig. 5 with a considerable pressure causing it to frictionally grip or bind against the edges of the side walls 9 of the arm 2 to resist the pressure of the spring 70 when it has been contracted by the retraction of the pusher 66. Stated another way, the friction exerted between the forward end of the cover against the arm 2 by the spring 63 will retain the cover and the pusher in retracted position against the increased tension of the spring 70 so that a stick or refill of staples, indicated at S in Fig. 5, may be inserted into the magazine 2 through the opening 40 in the staple-applying arm 3. Referring to Fig. 5, it will be observed that the purpose of the slit in the spring 63 is to permit the finger or lug 75 to slide back therethrough when the pusher 66 is slid into its rearward position illustrated in Fig. 5.

After the pusher 66 has been retracted in the manner explained above and the stick S of staples has been inserted through the opening 40 in the arm 3, as indicated in Fig. 5, and placed in position with the legs of the staples straddling the core 15, the cover 60 is slid forwardly on the magazine 2 into the position illustrated in Fig. 2 where its forward end brings up against the guard member 22. The cover 60 will thus serve to hold the staples from riding up on the core 15 and the implement is ready for operation. To apply a staple to the work the implement is grasped with the palm of the hand overlying the staple-applying arm 3 and the fingers pressing against the rounded under side of the operating lever 5. Then by applying pressure to the lever 5 its hooked connection with the studs 45 on the arm 3 will act to swing the latter and the clincher-arm 4 toward each other. During this relative movement between the arm 3 and arm 4 the leaf-spring 55 is compressed, but the spring 63 will resist relative movement between the arm 3 and the magazine-arm 2. When, however, the forward end of the magazine-arm is brought into contact with the work W, indicated in Fig. 12, the arm 3 will continue its motion to compress the spring 63. The motion of the arm 3 relative to the magazine-arm 2 will cause the staple-driver 25 to be slid downwardly in the grooves 21 at the forward end of

the magazine-arm. When the magazine is first supplied with staples s , that is unless staples already remain therein, the first action of the staple-driver 25 will be to separate a staple s from the stick S and carry it down onto the detent-shoulders 24 . That is to say, as the driver 25 descends the shoulder 30 on its rearward face will engage the crossbar of the foremost staple s in the series on the core 15 , see Figs. 10 and 12, to shear this staple from the strip and carry it down onto the detent-shoulders 24 . During this action of the driver its edge or shoulder 30 will compress the crowned top of the staple s to straighten it, thereby causing its opposite legs to be spread apart as shown at x in Fig. 13. This compression of the top of the staple will act to spread its legs against the inner faces of the sides 8 of the arm 2 directly beneath the inwardly-projecting lugs 31 so that the lugs will prevent the staple from rising to any extent above the detent-shoulders 24 .

The staple separated from the strip and moved into reserve position resting on the shoulders 24 beneath the lugs 31 thus will be retained in this position until the driver 25 is raised again by release of the pressure on the lever 5 . As the rearward edge 28 of the driver 25 rises above the shoulders 24 , see Figs. 10 and 11, the staple s resting on the shoulders 24 will be pushed off therefrom by the legs of the next succeeding staple on the core 15 as the whole series of staples is advanced by the pusher 66 . At the next descent of the staple-driver 25 , as the implement is again operated, the driver will engage the top of the staple s advanced into position beneath its edge 28 to force it down in the grooves 21 and drive it through the work as its legs are bent inwardly by the curved clinched-grooves 83 and clinched on the under side of the work, see Figs. 12 and 13. The purpose of this form of construction and arrangement of the parts is the same as that shown and described in a prior copending application, Serial No. 563,499, filed by Arthur H. Maynard November 15, 1944, issued on May 20, 1947, as U. S. Letters Patent No. 2,420,830, the present invention embodying simplification and improvement thereover. The object of this arrangement is to prevent a second staple being driven before the first one has been discharged from the machine or, in other words, to avoid driving one staple on top of another which would be liable to clog the machine. It will be observed that if the driver 25 should be depressed insufficiently to complete the driving and clinching of a staple, a second staple could not be entered into the grooves beneath the driver until the latter has completed the application of the first staple, that is, the staple being driven and remaining in the grooves beneath the driver will prevent another staple being fed off from the detent-shoulders 24 .

The implement may be operated continuously in the manner explained above to apply staples to the work in multiple and usually a fresh supply is inserted in the magazine before all the staples have been exhausted therefrom; the opening 40 in the arm 3 and the slot 62 in the cover 60 permitting inspection by the operator to reveal the number of staples remaining in the magazine at any time, see Figs. 2 and 4.

Fig. 14 of the drawings illustrates the present implement as having a modified form of clinching means to adapt it for clinching the legs of staples in stitching or tacking the cuffs of trousers to the legs thereof. In this modified form of construction the clincher-arm 80 is of slightly dif-

ferent form without a cylinder-block at its forward end. The clinching means comprises an auxiliary arm 81 pivoted at its rearward end to the crosspin 50 and having its forward end bent upwardly and rearwardly in an overlying portion 82 formed on the top with clincher-grooves 83 . A leaf-spring 84 having its rearward end bearing against the under side of the magazine-arm 2 has its forward end bifurcated to underlie shoulders 85 at the sides of the arm 81 . The spring 84 has a finger 86 sheared from its main portion and bent downwardly with its end curved to underlie the semicircular end portion of the arm 81 which engages around the under side of the pin 50 . The spring 84 thus acts to hold the arm 81 in pivotal connection with the main arm 80 while also tending to elevate the outer end of the arm 81 as shown by full lines in Fig. 14. The clinching means last described operate in substantially the same manner as explained in my prior patent, No. 2,354,760, referred to above, to adapt the inwardly-extending portion 82 of the arm 81 to be inserted between the folds of the cuff and trouser leg so that the staple may be inserted and clinched without its legs projecting through the outer layer of the cloth.

The last-described modified form of the implement is operated in substantially the same manner as that described above except that the clinching means acts to clinch the legs of a staple in a blind stitch so that they will not protrude from certain of the laminations of the work, such as for attaching the cuff to the leg portions of trousers without projecting the legs of the staple through the outer cuff-layer.

It will be observed from the foregoing specification that the present invention provides an extremely simple and compact form of implement 40 of the plier-type for applying fasteners while operating it in one hand. The structure and arrangement of the parts of the implement are considerably simplified and improved over previously used devices of the same type to render 45 the implement more economical to manufacture without loss of efficiency in its operation. Moreover, the improved implement provides for more convenient loading of the magazine with fasteners or staples; the cover member being adapted to be withdrawn to open the magazine while at the same time acting to retract the staple-pusher. In other words, the cover is operated for both functions of opening the magazine and retracting the pusher and the latter is held in retracted position without requiring any particular manipulation of the parts.

It is to be understood that while the present improvements are shown as applied to a plier-type of stapling implement they may be adapted 60 for fastener-applying devices of other types and therefore the invention is not limited in respect to its particular use as herein shown. Likewise, various modifications may be made in the structure and arrangement of the parts of the implement without departing from the spirit or scope of the invention. Therefore, without limiting myself in this respect, I claim:

1. In a fastener-applying implement, a magazine for supporting a supply of fasteners, a cover overlying the magazine for preventing displacement of the fasteners supported thereby, said cover being manually slidable longitudinally of the magazine to provide for loading it with fasteners, and resilient means acting against the top of the cover for holding the cover in place

on the magazine and applying frictional resistance to its sliding movement.

2. In a fastener-applying implement, a channel-shaped magazine for containing a supply of fasteners, a cover overlying the magazine for retaining the fasteners therein and slidably longitudinally thereof to open the magazine, and resilient means bearing against the cover for holding the cover against the magazine and applying frictional resistance to its sliding movement to retain it in position with the magazine open or closed.

3. In a fastener-applying implement, a channel-shaped magazine having a bottom and upstanding sides, a cover overlying the top of the sides of the magazine and slidable longitudinally thereof, a spring bearing against the cover to press it against the sides of the magazine and apply frictional resistance to its sliding movement thereon, and means for supporting the spring above the cover.

4. In a fastener-applying implement, a magazine for supporting a supply of fasteners, an arm extending above the magazine, a cover underlying the arm and overlying the magazine to prevent displacement of the fasteners supported thereby, said cover being slidable longitudinally of the magazine to provide for loading it with fasteners, and a spring acting between the arm and cover to maintain the cover in position on the magazine and apply frictional resistance to its sliding movement.

5. In a fastener-applying implement, a hollow magazine for supporting a supply of fasteners, an arm hinged to the end of the magazine and extending longitudinally thereabove, said arm having a longitudinally-extending opening in its top, a cover overlying the top of the magazine to prevent displacement of the fasteners therein, said cover being slidable longitudinally of the magazine to open it for receiving a supply of fasteners inserted through the opening in the top of the arm, and resilient means for maintaining the cover in either open or closed position on the magazine.

6. In a fastener-applying implement, a hollow magazine for supporting a supply of fasteners, an arm pivoted to the end of the magazine and extending longitudinally thereabove, said arm having an opening in its top, a cover underlying the arm and overlying the magazine for preventing displacement of the fasteners therein, and a spring between the arm and cover for maintaining the latter in place on the magazine and frictionally resisting its movement longitudinally thereof, said cover being slidable rearwardly on the magazine to open it for receiving a supply of fasteners entered through the opening in the arm.

7. In a fastener-applying implement, a channel-shaped magazine having upstanding sides, an arm of inverted channel shape having its sides pivoted to the sides of the magazine at one end thereof, a cover overlying the sides of the magazine and slidably longitudinally thereof between the sides of the arm, and a spring tensioned between the arm and cover for maintaining the latter in position on the magazine and frictionally resisting its sliding movement longitudinally thereof.

8. In a fastener-applying implement, a magazine for supporting a supply of fasteners, a cover overlying the top of the magazine to retain the fasteners in position and prevent their displacement, said cover being slidable longitudinally of

the magazine to open it for receiving a supply of fasteners, resilient means for pressing the cover down on the magazine and frictionally resisting its sliding movement longitudinally thereof, a pusher in the magazine for feeding the fasteners forwardly therein, a spring for advancing the pusher, and means on the pusher engageable by the cover to retract the pusher when the cover is slid to open the magazine.

10. 9. In a fastener-applying implement, a channel-shaped magazine for containing a supply of fasteners, an arm of inverted channel shape pivoted to the rearward end of the magazine with its sides overlying the sides thereof, a pusher slidably in the magazine for feeding the fasteners forwardly, a spring for advancing the pusher in the magazine, a cover overlying the top of the magazine to retain the fasteners therein, a spring within the arm acting against the cover to hold it down on the magazine and frictionally resist its sliding movement longitudinally thereof, said cover having a slot extending longitudinally thereof, and means on the pusher projecting through the slot in the cover and adapted to be engaged by the end of said slot to cause the pusher to be retracted when the cover is slid to open the magazine.

10. In a fastener-applying implement, a channel-shaped magazine for containing a supply of fasteners, an arm of inverted channel shape pivoted to one end of the magazine with its sides overlapping the sides thereof, a cover enclosed within the sides of the arm overlying the top of the magazine, a spring within the arm acting against the top of the cover to hold it in place in the magazine and resist its sliding movement thereon, and cam-faces between the cover and magazine adapted to lift the rearward end of the cover when it is slid longitudinally to open the magazine whereby to cause the spring to apply frictional resistance to the forward movement of the cover after it has been withdrawn to open the magazine.

11. In a fastener-applying implement, a channel-shaped magazine for containing a supply of fasteners, a cover overlying the top of the magazine to prevent displacement of the fasteners therein and slidably longitudinally thereof to open the magazine, resilient means for holding the cover pressed against the top of the magazine, notches having inclined edges at the sides of the magazine, and beveled shoulders on the cover adapted to ride up the edges of the notches in the sides of the magazine when the cover is withdrawn rearwardly thereof.

12. In a fastener-applying implement, a hollow magazine for supporting a supply of fasteners, and a lever movable relatively of the magazine and having a rectangular opening in its top wall extending longitudinally thereof and of substantial length through which the fasteners may be supplied to the magazine.

13. In a fastener-applying implement, a hollow magazine for supporting a supply of fasteners, and an arm hinged to the end of the magazine and extending longitudinally thereabove, said arm having a longitudinally extending opening of substantial length in its top to provide for loading the magazine with fasteners.

14. In a fastener-applying implement, a hollow magazine for holding a supply of fasteners, said magazine having a throat at one end through which the fasteners are driven, a pusher in the magazine for advancing the staples to the throat, and a lever hinged to the end of the magazine

11

and provided with a rectangular opening in its top wall extending throughout substantially one-half the length thereof through which the fasteners may be supplied to the magazine.

CHARLES M. LINDSTROM.
